[57] CLAIM

The ornamental design for a telephone station set base, substantially as shown and described.

DESCRIPTION

FIG. 1 is a top front perspective view of a telephone station set base showing our new design;

FIG. 2 is a top rear perspective thereof;

FIG. 3 is a rear elevation thereof;

FIG. 4 is a front elevation thereof;

FIG. 5 is a top plan view thereof; and

FIG. 6 is an end elevation thereof, the opposite end being a mirror image of the end shown.

FIG. 1

FIG. 2

FIG. 3

FIG. 4

FIG. 5

FIG. 6
